Attorney

UNITED STATES PATENT OFFICE

PAUL BIDAL, OF PARIS, FRANCE

TELESCOPIC SOCKET WRENCH

Application filed August 15, 1928, Serial No. 299,791, and in France August 22, 1927.

This invention has for its chief object to provide a socket wrench of telescopic or expandable structure adapted to ensure a powerful leverage when in use and to only occupy a minimum space, for example for storage in the tool box of an automobile, when out of use.

In the accompanying drawings forming a part of this specification:

Figure 1 is a perspective view of a telescopic socket wrench embodying the invention and provided with a removable socket member shown in operative position in dotted lines.

Figure 1^a is a perspective view of a portion of the slide of the wrench, showing a lug for limiting the motion of the handle thereon.

Figure 2 is a side elevation of the wrench showing it retracted with its reversible handle in two different positions.

Figure 2^a is a cross-section on the line $x-x$, Fig. 2.

Figure 3 is a similar side elevation of the wrench showing it expanded with its reversible handle in another or operative position.

Figure 4 is a detail sectional view showing stop means for limiting the outward telescopic motion of the slide.

Figure 5 is a part cross-section on the line $y-y$, Fig. 4.

Figure 6 is a similar view to Fig. 4 showing a modification of the stop means.

Figure 7 is a plan view showing a detail of the stop means illustrated in Fig. 5.

The same reference characters denote the same parts in all the figures.

A designates the socket or box member of the wrench, having an internal cross-sectional shape and size adapted to match the nuts or similar members to be tightened or loosened. This socket member A may be cast integrally with the shank a of the wrench or removably fitted on its end, preferably elbowed or cranked at a' as shown and held thereon by any approved means, as for example by a spring-pressed ball-detent b housed in the end of the shank a and slightly protruding therefrom for yieldingly engaging the inner wall of the socket tail.

As will be seen, the shank a of the wrench is formed in the embodiment shown of a solid

prismatical bar made of steel or other suitable hard metal. This prismatical shank a engages telescopically but non-revolubly a hollow prismatical slide C, advantageously made of drawn steel, open at both ends and whose bore snugly matches the cross-sectional shape and size of the shank a.

The wrench is completed by a reversible metal handle B arranged substantially at right angles to the slide and comprising a prismatical hub d shaped and sized so as to be freely movable along said slide. As shown in Figs. 1, 2 and 3, adjacent one of its ends the prismatical slide C is cylindrically shaped over a short portion of its length as at e, the diameter of this cylindrical portion substantially corresponding to that of the circumference that is circumscribed in the prismatical or polygonal contour of the hub d of the handle B (see Fig. 2^a) ; this cylindrical portion e is advantageously provided on the slide C at a distance equal to about twice the width of the hub d and is as long as said hub.

The handle B is slid onto the prismatical outer end portion of the slide C when the wrench is to be used i. e. when the shank a has been telescopically slid out of the slide C to the maximum extent. In order to stop the handle on said outer prismatical end portion, the latter is flanged at C' or provided with a similar projection. Moreover in order to limit the inward stroke of the handle B along the slide, the handle is provided midway of its width with a spring-pressed ball-detent f slightly protruding into the prismatical bore of its hub d, and adapted to engage a corresponding depression in the outer wall of the slide C. Alternatively, the slide C may be terminally fitted, as shown in Fig. 1^a, with a lug or like projection h adapted to stop the inward stroke of the handle B therealong.

To limit the outward stroke of the slide C with respect to the shank a, stop means are provided. Said means may take any approved form, two of which being exemplified in Figs. 4 to 7.

According to the embodiment shown in Figs. 4 and 5, the shank a is formed adjacent its free end with an incurved recess p' in

which is housed a segmental bolt p submitted to the outward push of a plunger r acted upon by a coil spring o housed in a slanting side extension m of the recess p' . A step like notch q is formed in the internal wall of the slide C adjacent its inner end whereby the engagement of the bolt p and notch q firmly stops the outward stroke of the slide C with respect to the shank a while permitting the slide C to be retracted inwardly by collapsing the bolt p into its recess p' against the coil spring o .

According to the other embodiment shown in Figs. 6 and 7, the shank a is formed adjacent its free end with a quadrangular recess m into which can freely penetrate a bolt p having a slanting upper face in the outward direction and constantly subjected to the outward push of a coil spring o abutting on the bottom of said recess. The internal wall of the slide C is formed adjacent its inner end with a step like notch q with which the bolt p can engage, as described with reference to Figs. 4 and 5.

25 To limit the inward stroke of the slide C with respect to the shank a preferably so that the outer end of the latter should come flush with the flange C' formed on the outer end of the slide C , a spring-pressed ball-detent f' is housed adjacent the outer end of the shank a and there is formed in the slide adjacent its outer end a corresponding depression or hole into which the ball f' can snap and thus hold the shank and slide locked against any further motion. The ball f' can be readily disengaged from the said depression or hole and the shank and slide thus freed from each other by manually pulling them apart with a sufficient-tractional stress.

40 It will be appreciated that numerous minor constructional details of this improved telescopic socket wrench might be changed without departing from the spirit of the invention as set forth in the subjoined claims.

45 Thus for instance the word "prismatical" as applied to the cross-sectional shape of the shank and slide must be broadly construed as involving any telescopically but non-revolubly interengaging contours. Further the stop means for limiting the inward and outward strokes of the slide with respect to the shank might be varied. The means for arresting the motion of the handle along the slide might also be varied.

55 What I claim is:—

1. A telescopic socket wrench comprising, in combination, a socket-carrying shank, a hollow slide having a bore matching the cross-sectional shape of the shank so as to telescopically but non-revolubly engage it and also having a non-circular exterior and a more limited circular portion, a handle mounted on the slide and formed with a hub having a bore matching the outer contour of the slide so as to engage it slidably through-

out its length and revolvably over a short portion of the length of said slide, stop means for limiting the outward and inward strokes of the slide along the shank, and stop means for limiting the outward and inward strokes of the handle along the slide. 70

2. A telescopic socket wrench comprising, in combination, a socket-carrying shank, a hollow slide having a bore matching the cross-sectional shape of the shank so as to telescopically but non-revolubly engage it, said slide having a prismatical cross-sectional contour over the greater portion of its length and presenting over a short portion of its length a circular contour cross-sectionally circumscribed in said prismatical contour, a handle mounted on the slide and formed with a hub having a prismatical bore matching the prismatical contour of the slide so as to engage it slidably throughout its length and revolvably over its short circular portion, stop means for limiting the outward and inward strokes of the slide along the shank, and stop means for limiting the outward and inward strokes of the handle along the slide. 80

3. A telescopic socket wrench comprising, in combination, a shank terminally cranked at right angles, a socket member removably fitted on the cranked end of the shank, a hollow elongated slide provided at both ends with projections and having a bore matching the cross-sectional shape of the shank so as to telescopically but non-revolubly engage it, said slide having a prismatical cross-sectional contour over the greater portion of its length and presenting over a short portion of its length a circular contour cross-sectionally circumscribed in said prismatical contour, a handle angularly mounted on the slide and formed with a hub having a prismatical bore matching the prismatical contour of the slide so as to engage it slidably throughout its length and revolvably over its short circular portion, a spring-actuated bolt housed in a recess formed in the prismatical surface of the shank and adapted to snap into a corresponding notch formed in the internal wall of the inner end portion of the slide, and a spring-pressed ball-detent housed in the outer end portion of the shank and adapted to snap into a corresponding depression formed in the internal wall of the outer end portion of the slide. 100

4. A telescopic socket wrench comprising, in combination, a shank terminally cranked at right angles, a socket member removably fitted on the cranked end of the shank, a hollow elongated slide provided at both ends with projections and having a bore matching the cross-sectional shape of the shank so as to telescopically but non-revolubly engage it, said slide having a prismatical cross-sectional contour over the greater portion of its length and presenting over a short portion of its length a circular contour cross-sectionally 120

circumscribed in said prismatical contour, a handle mounted at right angles on the slide and formed with a hub having a prismatical bore matching the prismatical contour of the slide so as to engage it slidably throughout its length and revolvably over its short circular portion, an arcuate bolt housed in a recess formed in the prismatical surface of the shank and acted upon by a coil spring housed in a side extension of said recess so as to snap into a corresponding step notch cut in the internal wall of the inner end portion of the slide, and a spring-pressed ball-detent housed in the outer end portion of the shank and adapted to snap into a corresponding depression formed in the internal wall of the outer end portion of the slide.
